(57) **CLAIM**

The ornamental design for a foldable bottle, as shown and described.

DESCRIPTION

FIG. 1 is top, front and right perspective view of the foldable bottle showing my new design;

FIG. 2 is a front elevation view thereof;

FIG. 3 is a right side elevation view thereof, the left side view being a mirror image;

FIG. 4 is a rear elevation view thereof; and,

FIG. 5 is a top plan view thereof.

The broken lines are included for the purpose of illustrating portions of the foldable bottle that form no part of the claimed design.
